J. B. A. LA JEUNESSE.

WEATHER STRIP,

APPLICATION FILED JULY 13, 1918.

1,342,050.

Patented June 1, 1920.

UNITED STATES PATENT OFFICE.

JEAN B. A. LA JEUNESSE, OF ALAMEDA, CALIFORNIA.

WEATHER-STRIP.

1,342,050.

Specification of Letters Patent.

Patented June 1, 1920.

Application filed July 13, 1918. Serial No. 244,719.

To all whom it may concern:

Be it known that I, JEAN B. A. LA JEUNESSE, of Alameda, California, have invented certain new and useful Improvements in 5 Weather-Strips, whereof the following is a specification.

This invention relates particularly to a weather strip especially designed for use in connection with doors for the exclusion of 10 wind, rain and the like, from between a door and its threshold, and it may also be used in connection with window shutters and other closures.

One of the objects of this invention is to 15 provide a vertical movable weather strip housed within a recess running along the bottom of a door, said weather strip being automatically elevated when the door is opened to allow a free swing of the latter.

Another and more specific object of the 20 invention is to provide in a weather strip of this nature operating means which will raise and lower the strip without moving it longitudinally.

The invention also aims to generally improve weather strips to render them more 25 useful, practical and commercially desirable.

With these and other objects in view as 30 will become apparent as the description proceeds, the invention consists in certain novel features of construction, combination and arrangement of parts as will be hereinafter fully described, illustrated and claimed at the end hereof.

In the drawings:—

Figure 1 is a fragmentary vertical sectional view through a door showing my improved weather strip mounted thereon and in elevated position.

Fig. 2 is a view similar to Fig. 1, with the weather strip lowered in contact with the threshold of the door.

Fig. 3 is a vertical sectional view.

Fig. 4 is a section on the plane of line 45 4—4 of Fig. 3, and

Fig. 5 is a section similar to Fig. 4, showing the door partially opened.

Referring in detail to the drawings by 50 numeral, 1 designates a door having a longitudinal channel or recess 2 formed in the lower edge thereof, which recess is prefer-

ably covered along its top and outer side by the metallic lining 3.

The door swings over the threshold 4 and when closed abuts against the jamb 5 which is formed with the recess 6 shown in Figs. 4 and 5 for a purpose to be herein-after explained.

Within the recess or channel 2 is mounted 60 a weather strip 7 in the form of a rectangular plate, which extends substantially the full length of the channel. The plate is slidably secured to the outer wall of the channel for vertical movement thereon by a plurality of studs 8, 9 and 10, having 65 heads 11. Each of the studs extends through a vertical transverse slot 12 formed in the plate 7, whereby it is apparent that the plate is capable of being moved vertically.

When the door is closed, the plate automatically lowers into contact with the threshold 4 to close the crack at the bottom of the door, and when the door is opened the plate is elevated above the threshold 70 so as not to interfere with the swing of the 75 door. The means which I have provided for thus raising and lowering the plate 7, include a lift or rocker arm 13 pivotally secured at one end to the stud 10 and extending longitudinally of the plate toward its 80 other end. This arm is slotted as indicated at 14 to permit passage of the stud 9 and is pivotally connected at its inner end to a link 15 by means of a pivot or stud 16, which passes through the link and arm and 85 is attached to the weather strip 7. Another link 17 is pivotally secured to the pivot or stud 18 carried by the outer wall of the channel 2 and is pivotally connected at one terminal to the corresponding terminal of 90 the link 15 by a pivot or stud 19 forming with said link 15 a toggle joint. A rod 20 is mounted within the door adjacent its free edge and extends from the channel 2 upwardly to an edge opening chamber 21. A 95 crank arm 22 is carried by the lower end of the rod 20 within the channel 2 and is pivotally connected to one end of a connecting rod 23 which is connected to the toggle by the stud 19 thereof. An expansive 100 helical spring 24 encircles the connecting rod 23, bears at one end against a washer 25, and

at its other end against an angular flange 26 formed on an arm 27 which is pivoted at one end to the stud 9. The flange 26 is apertured to accommodate the connecting rod 23.

5 An arm or extension 28 is provided at the upper end of the rod 20 and projects outwardly from the chamber 21 sufficiently far to strike against the end wall 29 of the recess 6, shown in Figs. 4 and 5, when the door is closed. When the door is opened the extension 28 is freed from engagement with the wall of the recess 6 and the spring 24 can then expand to draw the rod inwardly and throw the toggle members 17 and 15 into position shown in Fig. 1. This movement of the toggle throws the stud 16 upwardly and the stud being attached to the plate 7 raises the latter from lowered position into inoperative position as shown 10 in Fig. 1. Now, when the door is swung shut, the extension 28 strikes against the inner end wall of the recess 6, causing the rod 20 to rotate and move the connecting rod 23 longitudinally and bring the toggle members 17 and 15 into alinement as shown in Fig. 2, which movement lowers the stud 16 causing the strip 7 to be forced downwardly against the threshold 4. The rocker or lift arm 13 forms an important 15 feature of the invention, since it gives to the weather strip or plate 7 a vertical movement with but a very slight longitudinal movement. In fact, the longitudinal movement is so little as to be a practically negligible quantity and no special provision need be made therefor, as there will be sufficient play allowed by the slots 12 to accommodate this longitudinal displacement.

40 From the foregoing description taken in connection with accompanying drawings, it will be apparent that I have provided a very practical and efficient weather strip for doors, windows, and other closures, which is automatically moved into inoperative position when necessary.

Having thus described my invention, and an embodiment of it, in the full, clear and exact terms required by law, and knowing that it comprises novel, useful and valuable 45 improvements in the art to which it pertains, I here state that I do not wish to be limited to the precise construction and arrangement of the several parts, as herein set forth, as the same may be variously modified by a skilled mechanic without departing from the spirit of the invention.

What I claim and desire to secure by Letters Patent of the United States, is the following, to wit:—

60 1. In combination with a door and the jamb thereof, said door provided with a channel at its lower edge, a weather strip mounted for vertical movement in said channel, mechanism including a toggle joint for

normally holding the weather strip in elevated position located in said channel, a vertical rod connected to said toggle at one end by a longitudinal rod and having at its opposite end an arm engaging said jamb and thereby operating said toggle. 65

2. In combination with a door, a weather strip mounted for vertical movement thereon, means for operating said strip consisting of an arm pivotally connected at one end to the door and loosely connected at 70 its other end to the weather strip, a toggle pivoted to said door and engaging said arm for raising and lowering said arm when the door is open or closed and means for operating said toggle. 75

3. In combination with a door, a weather strip mounted for vertical movement thereon, an arm pivoted to said door and to the weather strip, said arm extending longitudinally of the weather strip and being 80 adapted when swung to move the weather strip vertically, mechanism including a toggle joint for swinging the arm upwardly when the door is opened and means for spreading said toggle joint to lower the 85 arm and weather strip when the door is closed. 90

4. In combination with a door, a weather strip extending transversely thereof and formed with a plurality of vertical slots, 95 studs mounted on the door and extending through said slots to slidably secure the weather strip in position, an arm extending longitudinally of the weather strip and adapted to swing in a substantially vertical 100 plane, means connecting the swinging end of said arm to the weather strip, a toggle joint connected to the door and to said arm, means for breaking said toggle to elevate the arm when the door is open and 105 means for straightening said toggle when the door is closed and lowering said arm. 110

5. In combination with a door, a weather strip mounted for vertical movement thereon, an arm mounted to swing in a substantially vertical plane, the swinging end of 115 said arm being connected to the weather strip, a toggle joint connected at one end to the door and at its other end to said arm, a longitudinally movable rod for collapsing and spreading said toggle joint, and means dependent for action on the position of said door for shifting said longitudinally movable rod.

6. In combination with a door having a 120 channel formed in the lower edge thereof, a weather strip mounted in said channel, a toggle joint connected to said strip and to the door, a longitudinal movable rod connected to the toggle, means for moving said longitudinal movable rod in one direction 125 for expanding the toggle joint when the door is closed consisting of a vertical rod

located within said door having at one end a crank arm and at its opposite end an arm engaging a recess in the jamb of the door and spring means for moving the longitudinally movable rod in the opposite direction to collapse the toggle joint when the door is open.

In testimony that I claim the foregoing I have hereto set my hand this 29th day of June, 1918, in the presence of witnesses.

JEAN B. A. LA JEUNESSE.
